(57) **CLAIM**

The ornamental design for a image processor, as shown and described.

DESCRIPTION

FIG. 1 is a top, front and left side perspective view of an image processor showing my new design;

FIG. 2 is a top, rear and right side perspective view thereof;

FIG. 3 is a front elevational view thereof;

FIG. 4 is a rear elevational view thereof;

FIG. 5 is a top plan view thereof;

FIG. 6 is a bottom plan view thereof;

FIG. 7 is a left side elevational view thereof;

FIG. 8 is a right side elevational view thereof; and,

FIG. 9 is a top, front and side perspective view thereof in a manner of use shown at a reduced scale.

The broken lines shown in FIG. 6 represent portions of the image processor that form no part of the claimed design.

The broken lines shown in FIG. 9 represent portions of the image processor that form no part of the claimed design.
